2,346,118

APPARATUS FOR SEALING CONTAINERS

Harry E. Stover, Connellsville, Pa., assignor to
 Anchor Hocking Glass Corporation, Lancaster,
 Ohio, a corporation of Delaware

Application November 8, 1941, Serial No. 418,401

10 Claims. (Cl. 226—82)

My invention relates to an apparatus for sealing containers. It has to do, more particularly, with an apparatus for applying closures to containers, such as food containers and including jars, bottles, cans, et cetera, and sealing them on the containers and for producing a partial vacuum in the upper ends of the containers.

This application is a continuation-in-part of my copending application, Serial No. 349,655, filed August 2, 1940, and which matured into Patent No. 2,321,779, June 15, 1943. In the said Patent No. 2,321,779 I disclose apparatus for applying closures to and sealing them on various containers. The apparatus is disposed in superimposed relationship to a continuously-moving conveyer upon which the filled containers are placed at random. The apparatus may include a cap feeding and applying unit where caps or other closures are loosely positioned on the upper ends of containers moved into association therewith by the conveyer. Directly adjacent this unit a sealing unit is provided. The conveyer moves the containers with caps loosely applied thereto, into association with a sealing head forming a part of the sealing unit. The sealing head is spaced slightly above the upper ends of the containers and fluid-actuated means is associated therewith for forcing it downwardly whenever a container having a cap properly associated therewith, moves beneath the sealing head, a control arrangement is provided for starting operation of the sealing head at the proper instant.

The present invention deals with improvements in the operating mechanism for moving the sealing head between its upper non-sealing position and its lower sealing position. It also deals with improvements in the control mechanism which initiates and controls movement of the sealing head.

Instead of providing a toggle structure for connecting the sealing head to the cylinder and piston actuating unit as in Patent No. 2,321,779, I provide a reciprocable wedge structure. The wedge structure is reciprocated horizontally by the cylinder and piston unit and this movement causes vertical movement of a plunger which carries the sealing head. For initiating and controlling movement of the sealing head I provide a control mechanism in which the trigger mechanism of Patent No. 2,321,779 is eliminated.

The preferred embodiment of my invention is illustrated in the accompanying drawings, where-in similar characters of reference designate corresponding parts and wherein:

Figure 1 is a side elevational view of a machine constructed in accordance with my invention.

Figure 2 is a plan view of the machine shown in Figure 1.

Figure 3 is a horizontal sectional view taken substantially along line 3—3 of Figure 1 and showing the sealing head unit.

Figure 4 is a longitudinal vertical sectional view taken substantially along line 4—4 of Figure 2 illustrating the sealing head unit and its operating mechanism.

Figure 5 is a transverse vertical sectional view taken substantially along line 5—5 of Figure 2.

Figure 6 is a vertical sectional view taken substantially along line 6—6 of Figure 3 showing the means for lifting the cap before the container moves beneath the sealing head.

Figure 7 is a horizontal sectional view taken substantially along line 7—7 of Figure 4.

Figure 8 is a detail, partly in perspective and partly in vertical section, of the lower portion of the plunger which carries the sealing head.

Figure 9 is a vertical sectional view of the valve which is used for controlling operation of the sealing head, the valve being shown in its normal position.

Figure 10 is a similar view but showing the valve in its operative position.

Figure 11 is a view similar to Figure 7 but showing a modified form of valve.

Figure 12 is a view similar to Figure 8 but showing the modified form of valve.

With reference to the drawings, I have illustrated a machine which comprises generally a conveyer unit 1, a cap-feeding and applying unit 3 and a sealing head unit 3.

The conveyer unit 1 may be of any suitable type. For example, it may be of the type disclosed in the co-pending application of William D. Bell on Apparatus for sealing containers, Serial No. 314,299, filed January 17, 1940. However, it is to be understood that my apparatus may be associated with any suitable type of conveyer unit. The conveyer unit preferably embodies means for continuously moving the containers into proper association with the units 2 and 3, including means for centering the containers relative to said units. The cap-feeding and applying unit 3 may be of the type disclosed in my co-pending application Serial No. 349,655.

My invention is not limited to use with any particular type of container and cooperating cap but for illustrative purposes I have shown in Figure 5 a container 4 adapted to receive the cap 5 on its upper end. This cap preferably embodies

a substantially disk-like portion 6 which has a depending annular skirt 7 which carries an annular gasket 8 therewithin. When the cap is forced downwardly onto the upper end of the container, the frictional contact of the gasket with the upper end of the container will aid in maintaining the cap in position and will seal the cap on the container.

The containers 4 are placed indiscriminately on the conveyer and are moved in the direction of the arrows (Figures 1, 2, 4 and 6) by the conveyer. The containers are centered thereon in the manner described in said co-pending application Serial No. 314,299. They are first carried to the cap-feeding and applying unit 2. This unit is of such a type that it will apply a cap loosely to the upper end of the container. After the container passes the unit 2, it passes to the sealing head unit 3. This sealing head unit 3 is adapted to displace the air from the head space and to sterilize such space and the cap before the sealing operation.

The units 2 and 3 are disposed directly adjacent each other. They are both supported by a horizontally disposed plate 9. The plate 9 is supported at a point spaced above the conveyor unit 1 by means of four vertically disposed non-rotatable posts 10 two of which are disposed at the left-hand corners of the plate (Figure 1) and the other two of which are spaced a substantial distance from the right-hand end of the plate. Each of these posts 10 is provided with a base portion 11 on its lower end which is suitably secured, as by screw bolts 11a, to a portion of the conveyer unit 1. The upper portion of each of these posts is threaded, as indicated at 12. Each of the posts has an internally threaded worm gear 13 mounted on the threaded portion 12 thereon. Each of these worm gears is disposed within a socket formed in the plate 9. Formed integral with the left-hand end of plate 9 is a pair of bearing lugs 14 (Figure 2). Formed integral with the plate 9 adjacent its opposite end is a pair of bearing portions 15. The pair of bearing portions 15 rotatably support a horizontally disposed worm shaft 16. The pair of bearing lugs 14 at the other end of the plate 9 rotatably support a horizontally disposed worm shaft 17. Each of the worm shafts 16 and 17 carries a pair of worms 18 which engage the adjacent worm gears 13. The worm shaft 17 is provided with an angular end for receiving a crank 19 by means of which it may be rotated. In order to rotate the shaft 16 simultaneously with the shaft 17, the shaft 17 is provided on its opposite end with a sprocket 20 keyed thereon. This sprocket has a chain 21 passing therearound which also passes around a sprocket 22 keyed on the corresponding end of the shaft 16.

Thus, it will be apparent that when the shaft 17 is rotated, the shaft 16 will be rotated simultaneously and to the same extent. Consequently, by rotating shaft 17, all of the worm gears 13 will be caused to rotate. Since these gears are threaded on the posts 10, they will be moved vertically on the posts. Furthermore, since the gears are in engagement with surfaces of the plate 9, the plate 9 will be moved vertically in accordance with the vertical movement of the gears. Thus, the plate 9 may be adjusted vertically to position the units 2 and 3 at the proper height above the conveyer unit, depending upon the height of the containers to be sealed. It will be noted that all portions of my apparatus are carried by the plate 9. Consequently, it is in the form of a unitary structure which may be read-

ily associated with any suitable type of conveyer unit.

The sealing head unit 3 is illustrated best in Figures 1 to 8. It comprises a vertically disposed cylindrical housing portion 23, which has a base portion 24 that is bolted by means of bolts 24a to the upper surface of the plate 9. Beneath the base portion 24 (Figure 4), the plate 9 is provided with a large opening 25, in order to permit vertical movement of the sealing head 26. This sealing head embodies a substantially cylindrical portion of non-magnetic metal which is carried on the lower end of a plunger 27 which fits tightly within housing 23 for vertical reciprocation therein.

The sealing head 26 is provided with a recess 28 in its upper surface which receives the lower end of the plunger 27. The plunger carries an enlarged portion 29 (Figures 4 and 8) on its lower end which limits its upward movement by contacting with the lower end of housing 23. This enlarged portion 29 is notched on one side to provide a flat vertical surface 29a (Figure 8) with which a flat vertical surface of an aligning block 29b cooperates. Block 29b is disposed within opening 25 and is bolted to plate 9 by bolts 29c. The block serves to prevent rotation of plunger 27 and also to maintain a perpendicular stroke of the plunger. However, a key and spline arrangement may be provided for this purpose, if desired. The notch in portion 29 with which block 29b cooperates is of sufficient height to permit proper reciprocation of the plunger 27 without interference with block 29b. The plunger 27 is provided with a vertically disposed bore 30 (Figures 4 and 8) which has an interiorly threaded lower end that receives the threaded upper portion of a bolt 31. This bolt passes upwardly through a centrally disposed opening 32 in member 26 which is enlarged at its lower end to receive the head 33 of the bolt 31. The bolt 31 will maintain the head 26 in position on the lower end of the plunger 27. The lower portion of plunger 27 which fits into recess 28 of member 26 has its one side flattened, as indicated at 29d (Figure 8), to prevent rotation of member 26 on the member 27.

In order to normally maintain the plunger 27 in its uppermost position I provide the following structure. A pin 35 (Figure 4) is carried by the housing portion 23 and extends transversely thereof and through a vertically disposed slot 36 formed in the plunger 27. A compression spring 37 has its lower end resting on this pin 35 and its upper end engaging with the upper end of the bore 30. Thus, this spring 37 normally tends to force the plunger 27 upwardly until the enlarged portion 29 thereof contacts with the lower end of the housing portion 23.

Threaded into a collar 38, bolted by bolts 38a to the upper end of the housing portion 23, is a threaded sleeve 39 which has an integral hand-wheel portion 39a. This sleeve 39 has a plunger 40 mounted therein for slidable vertical movement. This plunger has an enlarged portion 41 on its lower end which fits tightly within the housing portion 23 for vertical movement therein. Between the lower end of the threaded sleeve 39 and the upper surface of the portion 41 and in surrounding relationship to the plunger 40, is a compression spring 42. The spring 42 normally forces the plunger 40 downwardly. The upper end of the plunger 40 is threaded, as indicated at 45, and receives a threaded collar 46 which bears against the upper end of the sleeve 39. The collar 46 may be rotated on the threaded portion 45

of plunger 40 so as to adjust plunger 40 axially through sleeve 39 and thereby properly locate the lower end of the plunger relative to the wedge member 49 described hereinafter. The collar 46 is normally prevented from turning by means of a set screw 46a having its lower unthreaded end extending for slideable vertical movement into any of a series of openings in the upper end of sleeve 39. To change the downward force exerted by spring 42 on the plunger, the sleeve 39 may be rotated in the collar 46 to change the distance between the upper end of portion 41 and the lower edge of the sleeve 39. When sleeve 39 is rotated, collar 46 is moved therewith because of screw 46a. Therefore, the position of threaded portion 45 of plunger 40 in sleeve 39 is not changed. The threaded sleeve 39 may be held in any adjusted position by means of a spring pressed plunger 48 extending through collar 38. Collar 46 is provided with a socket 46b for receiving a tool by means of which it may be rotated. Plunger 40 is prevented from rotating in housing 23 by the key 40a carried by the plunger 40 and extending into a vertical slot or keyway in member 23.

It will be apparent that the plungers 40 and 27 are disposed in axial alignment. It will also be apparent that the lower end of the plunger 40 is spaced above the upper end of plunger 27. The lower end of plunger 40 is bifurcated (Figures 4 and 5) and carries a roller 50 which projects beyond the extreme lower end thereof. The upper end of the plunger 27 is also bifurcated and carries a roller 52 which projects beyond the extreme upper end thereof. Between the rollers 50 and 52 a wedge member 49 is disposed. This wedge member 49 extends through oppositely disposed vertical slots 51 and 51a formed in the wall of housing 23. The wedge member 49 is adapted to be reciprocated. The wedge member 49 comprises a narrow outer end portion 53 which has a straight upper edge joined to the straight upper edge of an inner wide portion 54 by means of a sharply curved edge portion 55. The lower edge of portion 53 has a beveled outer portion 53a and a straight portion 53b which is joined to the wider portion 54 of the wedge member by means of a gradually inclined edge portion 55a.

The wedge member 49 is formed on the outer end of a piston rod 56. The slots 51 and 51a in the housing 23 are of sufficient height to permit the required vertical movement of the wedge member 49. The wedge member 49 is normally in the position indicated in Figure 4 with its outer end projecting through the slot 51a a substantial distance. Below this outer end 53 of the wedge member I provide a bumper or cushioning member 57. This member comprises a plunger, disposed in a extension 23b of housing 23, which is normally forced upwardly by means of a compression spring 57a which surrounds it and which is disposed within portion 23b. The spring normally keeps the upper end of member 57 above the housing portion 23b. This upper end carries a roller 57c. Lock nuts 57b threaded on the lower end of member 57 serve as adjustable stop members for limiting the uppermost position of member 57.

The actuating mechanism for the sealing head 26 is normally in the position illustrated in Figure 4. The plunger 40 will be held in its lowermost position by the spring 42. The plunger 27 will be held in its uppermost position by the spring 37. The wedge member 49 will be in the position illustrated in Figure 4. It will be apparent that if the

5 piston rod 56 is moved to the right (Figure 4), the wedge member 49 will exert a wedging action between the rollers 50 and 52. The spring 42 will be of such strength that normally it will not be compressed by this wedging action. Consequently, the plunger 27 will be forced downwardly against the action of the spring 37 and, therefore, will force the sealing head 26 downwardly. Movement of wedge member 49 to the right will cause its outer end 53 to swing downwardly as the sealing head and plunger 27 are forced downwardly. When the member 49 reaches the end of its stroke in this direction, the outer end 53 of member 49 will contact with the roller 57c of bumper 57 and will be cushioned by the bumper.

10 As soon as the piston rod 56 moves to the left, the spring 37 will return member 26 to its uppermost position. The spring-pressed plunger 48 is provided to limit the downward force exerted 20 on the plunger 27 to a predetermined maximum, so as to prevent injury to the container being sealed. This predetermined maximum is determined by the initial adjustment of the distance between the lower end of sleeve 39 and the portion 41 of plunger 40, which varies the downward force exerted by the spring 42. When the downward force created by the wedge member 49 on the plunger 27 reaches the predetermined maximum, the plunger 40 will be forced upwardly 25 against the resistance of the spring 42 since member 46 will move upwardly relative to member 39 but the lower end of screw 46a will still extend into the opening in member 39. Consequently, the pressure exerted on plunger 27 will not be excessive. Adjusting the plunger unit 40 vertically by means of the member 46, as previously described, will vary the extent of the downward movement of the plunger 27 and, consequently, of the member 26. Thus, the extent of the downward movement of member 26 may be readily 30 adjusted.

35 For controlling movement of the piston rod 56, I provide the mechanism now to be described. This mechanism comprises a fluid-operated cylinder and piston unit 59. This unit 59 includes a housing 59a which has a large cylinder bore 60 formed in its upper portion and a small cylinder bore 61 formed in its lower portion. The bores 60 and 61 are horizontally disposed and are parallel with each other. The housing 59a is mounted on the upper surface of the plate 9 directly adjacent the housing 23. It is provided with a flattened lower surface which rests on the upper surface of plate 9. To secure the housing 59a to the housing 23, the lower portion of housing 23 is provided with upwardly projecting lugs 23a (Figure 7), through which bolts 62 pass. Bolts 62 have their ends threaded into the housing 59a and spacers 63 are provided on the bolts. A bolt 65 (Figure 4) is passed horizontally through an upstanding lug 66 on the housing 59a and has its outer end threaded into a boss on the housing portion 23, as at 67. A spacer 68 is provided on the bolt 65. Thus, it will be apparent that the 40 housing 23 is held firmly in position with reference to housing 59a.

45 The bore 60 has a hollow piston 69 slidably mounted therein. The inner end of the piston rod 56 (Figures 4 and 7) is pivotally connected to piston 69 by means of a wrist pin 70. This pin 70 extends transversely through an opening in rod 56 into bosses 71a formed on the interior of the piston. In order to take the thrust of rod 56 from pin 70, a member 56a is provided. This member 56a has a concave socket or notch 75

formed in its inner end which receives the convex inner end 56c of the rod 56. Thus, rod 56 will bear against member 56a which will take the thrust from the pin 70. The member 56a has a pin extension 56d which extends through an opening in the closed or inner end of piston 69. A nut 70a is threaded on this extension 56d and holds the member 56a in position. The nut further serves to hold a lock washer 70b in a recess formed in the closed end of piston 69. The washer 70b will contact with the inner surface of the head 71, disposed at the left-hand end of housing 59a, in order to keep the end of the piston spaced from this head. The head 71 is provided with an opening in which nut 70a is disposed when piston 69 is in the position shown in Figure 4. Over this opening a spacer member 56e is disposed. This spacer member slidably receives the extension 56d. A cap 56f is disposed over extension 56d and is secured to head 71 by bolts 71b which also secure spacer member 56e thereto. A compression spring 56g surrounds extension 56d and has one end bearing against member 56e. The other end bears against a collar 56h which is loosely disposed on pin extension 56d. This collar bears against shoulder 56i formed on the inner surface of cap 56f. Nuts 56j are carried on the outer end of extension 56d. When piston 69 moves to the right, as it nears the end of its stroke, nuts 56j will contact collar 56h and spring 56g will be compressed, serving as a cushion or buffer. When the washer 70b becomes worn by contact with the inner surface of head 71, it may be removed readily and be replaced. Thus, the inner end of piston rod 56 is pivotally connected to piston 69 so that swinging movement of wedge 49 will be permitted during its reciprocation.

A cap 72 is bolted to the other end of the housing 59a and is provided with an opening 74. The piston rod 56 passes inwardly through this opening into the interior of the bore 60. The opening 74 is larger than the piston rod 56 so as to permit limited movement of the piston rod therein. A compression spring 77 is disposed within the bore 60 in surrounding relationship to the rod 56. One end of the spring bears against a flanged washer 73 which is disposed in a recess formed in cap 72 while the opposite end bears against a shoulder 78 which is formed on rod 56. It will be apparent that this spring normally tends to force the piston 69 to the left so that the washer 70b contacts with the head 71. When piston 69 is moved to the right (Figure 4) it will move the wedge 49 to the right until the sharply curved portion 55 reaches roller 50. This sharply curved portion will then serve to interrupt movement of rod 56 and wedge 49 and, consequently, the piston 69. The curved portion 55 is so located that it will prevent the right-hand end of piston 69 from contacting with the head 72.

I preferably employ steam as the fluid for moving the piston 69 from the position indicated in Figure 4. The housing 59a has a steam jacket 80 formed in the wall thereof and extending completely around the housing. A main steam line 81 (Figures 2 and 5) is adapted to convey steam into this jacket. This jacket serves to prevent or decrease condensation of the steam within the housing 59a. The jacket also serves as a source of supply for operating the sealing mechanism, as will later appear. The line 81 is connected to a suitable source of supply in a manner to be described.

The bore 61 has a piston type valve 82 mounted for axial movement therein, as shown best in Fig- 75

ures 4, 9 and 10. This piston valve 82 is adapted to control the supply of steam to and exhaust of steam from the cylinder bore 60. Intermediate its ends the piston valve 82 is provided with an annular chamber 83 and at its extreme ends the piston valve 82 is provided with projecting portions 84. An exhaust and inlet opening 85 is provided in the wall of the bore 61 intermediate the ends thereof and communicates with a longitudinal passageway 87. Opening 85 is always in communication with annular chamber 83. The passageway 87 has one end communicating with an opening 88 which leads into the cylinder bore 60 adjacent the head 71. The opposite end of the passageway 87 communicates with an opening 89 which leads through the wall of the bore 60. A longitudinally extending groove 90 is formed in the periphery of the piston 69. When the piston 69 is in the position indicated in Figure 9, the opening 89 will be closed by piston 69 and will not be in communication with a passageway 89a, formed in the wall of bore 60, but when the piston 69 moves to the position indicated in Figure 10, the groove 90 will be in such a position that it will connect opening 89 to passageway 89a. The opening 89 is uncovered by piston 69 when it is in the position shown in Figure 10.

At spaced points in the wall of the bore 61 an inlet opening 91 and an outlet opening 91a are formed. The inlet opening 91 is connected to an opening 92 leading from the steam jacket 80. The opening 91a leads to the atmosphere. With piston valve 82 in the position shown in Figure 9, the annular chamber 83 is in communication with exhaust opening 91a and piston 82 covers opening 91. With piston 82 in the position indicated in Figure 10, chamber 83 is in communication with inlet opening 91 and exhaust opening 91a is covered by the piston.

With the piston 82 in the position indicated in Figure 9, steam will exhaust from the left-hand end of the cylinder bore 60, through opening 88, passageway 87, opening 85, annular chamber 83, and exhaust opening 91a. The piston 82, when in the position indicated in Figure 9, will cover the inlet opening 91. Consequently, steam will not be supplied to the cylinder bore 60.

For controlling movement of the piston valve 82, I provide a valve mounted in an extension 94 of the housing 59a. This extension is preferably of the shape shown in Figure 4 but is shown diagrammatically in Figures 9 and 10. A cylindrical bore 96 is formed in the main portion of the extension 94. The bore 96 receives a piston 97, which is mounted for axial movement therein. The ends of the piston are provided with extension 98 and 98a which serve as stops for contacting the ends of bore 96. The piston 97 has a large central annular chamber 99 formed therein and small annular chambers 100 and 101 formed therein adjacent the ends thereof. A steam passageway 103 connects the steam chamber 80 at all times to the annular chamber 99 formed in the piston 97. An exhaust passageway 104 connects the bore 96 to the atmosphere. Spaced passageways 105 and 106 communicate with the bottom side of the bore 96 and, when the piston 97 is in the position indicated in Figure 9, the portion 107 of the piston covers the end of passageway 106 while the end of passageway 105 communicates with the chamber 99 in the piston. These passageways 105 and 106 are connected to a passageway 108 which is connected to the left-hand end of the cylinder bore 61. Axially spaced passageways 109, 110 and 111 communicate with

the bore 96 and, when the piston 97 is in the position indicated in Figure 9, the portion 107a thereof covers the end of passageway 109, the passageway 110 communicates with the annular chamber 99 of the piston 97, and the passageway 111 communicates with annular chamber 111a formed at the right-hand end of bore 96. The passageway 109 is connected to a passageway 112 which is connected to the right-hand end of the bore 61 and which has its end closed by projection 84 on piston 82. The passageways 110 and 111 are connected together by a passageway 112a which is controlled by a needle valve 112b threaded into housing portion 94. An exhaust passageway 104a leads from the right-hand end of bore 61 to the atmosphere. An exhaust passageway 111b leads from the right-hand end of bore 96 and is always in communication with chamber 111a.

It will be apparent that with the piston 97 in the position indicated in Figure 9, steam will flow from the chamber 80, through the passageway 103, through annular chamber 99 of piston 97, through passageways 105 and 108, to the left-hand end of the bore 61, and will force the piston 82 to the right. At the same time, any steam in the right-hand end of the bore 61 will exhaust through passageway 104a. Thus, the inlet opening 91 will be covered by the piston 82, while the exhaust opening 91a will be uncovered. Consequently, steam from the left-hand end of the cylinder bore 60 will exhaust through the opening 88, passageway 87, opening 85, chamber 83 and exhaust opening 91a. Thus, the spring 77 will be permitted to return the piston 69 to the position indicated in Figure 4.

However, if the piston 97 is moved to the left, as indicated in Figure 10, steam will be supplied to the left-hand end of the cylinder bore 60 to move the piston 69 to the right. It will be apparent that when the piston 97 is moved to the left, steam will flow from the passageway 103, through the annular chamber 99 in piston 97, through the passageway 109, through passageway 112 and will unseat portion 84 of piston 82 from the end of passageway 112, which will cause the piston 82 to move to the left. Thereafter, steam entering bore 61 through passageway 112 will exhaust through passageway 104a. Some of the steam entering chamber 99 through passageway 103 will flow through passageway 110, passageway 112a, passageway 111, chamber 111a into passageway 111b which will be closed at this time in a manner to be referred to later. The steam in the left-hand end of the bore 61, upon movement to the left of piston 82, will exhaust through the passageway 108, through passageway 106 (the end of passageway 105 being closed by the portion 107 of piston 97 at this time) through chamber 100 and through passageway 104 to the atmosphere. When the piston 82 is moved to the position indicated in Figure 10, the inlet opening 91 is uncovered while the exhaust opening 91a is covered. Consequently, steam will flow from the chamber 80 through opening 92, through opening 91 into chamber 83, through opening 85, passageway 87 and finally through opening 88, into the left-hand end of the bore 60. This will force the piston 69 to the right.

When the piston 69 moves to the right sufficiently, the opening 89 communicates with the passageway 89a through groove 90. This will permit steam to flow from passageway 87 into passageway 89a and into the bore 96a which is formed in the upper portion of extension 94 and which

communicates with the left-hand end of bore 96. This will force the piston 97 from the position indicated in Figure 10 into the position indicated in Figure 9 provided passage 111b is vented in a manner described hereinafter.

When the piston 97 is moved to the left (Figure 10), the piston 69 is moved to the right, as described above. However, as soon as the piston 69 moves sufficiently the piston 97 will be returned to its original position by steam pressure, as described above. The piston 69 will be returned to its original position, shown in Figure 9, by the force of spring 77.

For moving the valve piston 97 from the position indicated in Figure 9, in order to move the piston 69 and, consequently, the sealing wedge member 49, I provide the arrangement now to be described. This arrangement is illustrated in Figures 4 and 8 and diagrammatically in Figures 9 and 10. As shown in Figures 4 and 8, I provide a tube 115 which has its upper end clamped to housing portion 94 by clamping means 116. This tube is inclined downwardly and laterally towards the sealing head 26 and is provided with a vertical portion 117 which telescopes with the upper end of a small tube 118 which is disposed in a suitable opening in the head 26 and projects upwardly a substantial distance beyond the upper surface of the head. The flat portion 29d on the lower end of plunger 27 provides clearance for portion 117 of member 115. Vertical portion 117 of member 115 is provided with an opening 117a which is closed by the telescoping portion of tube 118 when the sealing head 26 is in its uppermost position. At the extreme lower end of tube 118 a small outlet opening 119 is provided at the lower surface of the head 26. The tube 118 and the tube 117 are provided with a continuous passageway 120 which communicates at its upper end with the passageway 111b formed in the housing 94. When the opening 119 is exposed and the valve piston 97 is in the position indicated in Figure 9, steam will escape from chamber 111a, through passage 111b, through passageway 120 and to the atmosphere through opening 119. This will also happen if opening 117a is uncovered but this will not happen until sealing head 26 is moved downwardly. Thus, the valve piston 97 will remain in such position. However, as soon as the opening 119 is closed by movement of the cap 5 into association with the sealing head, as shown in Figure 10, pressure will be built up in the chamber 111a and will force the valve piston 97 to the left, as shown in Figure 10. This will actuate the piston valve 82 and the piston 69, as previously described, and will actuate the sealing head 26. The amount of steam entering chamber 111a is controlled by the needle valve 112b. When the sealing head 26 moves downwardly, the upper end of tube 118 slides relative to portion 117 of tube 115 and will expose opening 117a as the sealing head nears its lowermost position. When the opening 117a is uncovered, the valve piston 97 will be returned to its original position shown in Figure 9 in the manner previously described. As soon as the cap 5 is moved from covering relationship with opening 119, this action will be aided. When sealing head 26 is again moved upwardly, opening 117a will be closed.

A drain 82a is provided for draining any condensate from bore 61 and this also acts as an exhaust to preclude a cushion of steam in the end of bore 61 from preventing member 82 from returning to the position shown in Figure 9.

Thus, when a cap moves into sealing position under the sealing head 26, the valve piston 97 is actuated which, in turn, actuates valve piston 82 and piston 69 in the manner illustrated in Figure 10. This actuates the sealing wedge 49 and the sealing head 26.

The cap-feeding and applying unit 2 may be the same as that disclosed in my co-pending application Serial No. 349,655.

When the conveyer moves a container beneath the cap-feeding unit 2, a cap will be applied loosely to the upper end of the container as described in my co-pending application. The cap and container will be moved along until they pass beneath the sealing head 26. In order to lift the cap from the container before it reaches the sealing head 26 to be sure that the cap does not stick on the container, I provide a plate 165 which is supported beneath plate 9 and extends from the cap feed 2 to the sealing head 26 as shown in Figure 6. This plate 165 has a plurality of longitudinally spaced magnets 166 which serve to lift the cap at intervals as the container is moved therebeneath towards the sealing head 26. The sealing head also has means associated therewith for lifting the cap slightly from the container. This means comprises a plurality of small magnets 174 (Figure 6) which are arranged in circumferentially spaced relationship and are of the same structure as magnets 166. All the magnets are of cylindrical form and are mounted in sockets formed in the head 26 or plate 165 which are of non-magnetic material. These sockets do not extend quite completely through the head 26 or plate 165. The upper end of each socket receives a cylindrical portion 176 of rubber which fits tightly therewith and tends to hold the magnet in position.

As the container with the cap thereon moves beneath the sealing head 26, the forward edge of the cap will first be lifted by a magnet 174. Continued movement of the container will cause the magnets to act on the cap to hold it up against the lower surface of the member 26. Even with the cap in firm contact with the member 26, the skirt of the cap will still surround the upper end of the container so that it will be moved along with the container. However, the cap will be spaced sufficiently from the upper end of the container to permit steam to be injected therein. When the cap moves over opening 119, the operation of the sealing head will be initiated in the manner previously described.

The means for injecting the steam into the upper end of the container comprises a pair of steam jet members 177 (Figure 5) which are provided with steam slots 178. The members 177 are in spaced parallel relationship and extend along the member 26. The members 177 are carried by arms 178c which are, in turn, carried by guide members 178d (Figures 4 and 5). These guide members 178d are suitably mounted in guideways 178e on the bottom of plate 9. A screw member 178f has oppositely threaded portions engaging the members 178d and is carried by the plate 9 in such a manner that it will not move axially. It will be understood that by rotating screw 178f the distance between the members 177 may be adjusted.

Each of the members 177 has a longitudinally extending passageway 179 (Figure 5) which communicates with the outlet slot 178. This passageway 179 is connected by means of a passageway 180 to a longitudinally extending tubular chamber 181. This chamber 181 receives a hollow tu-

bular electric heater 182. The heater 182 is of such a type that it will not be injured by moisture and is connected to a suitable source of power by means of a suitable conduit. A flexible conduit 184 (Figures 3 and 5) is connected to the chamber 181 of one of the members 177. The chamber 181 of this member 177 is connected to the chamber 181 of the other member 177 by means of a telescoping tube 185. Thus, steam will be supplied to both of the members 177 regardless of their position of adjustment. The steam entering the chambers 181 will pass around the heaters 182 and will be dried by such heaters. This eliminates the necessity of providing a steam super-heater of the type disclosed in said co-pending application S. N. 314,299.

The steam lines 184 and 81 are connected to steam supply control means disposed within housing 210 (Figure 5) supported by plate 9. This control means is the same as that disclosed in my co-pending application and is connected to a suitable source of steam supply.

From the preceding description, the operation of the entire machine will be well understood. The conveyer will be continuously driven and the plate 9 will be adjusted to the proper height above the conveyer depending upon the height of the containers to be sealed. The members 177 will be properly adjusted relative to each other depending upon the diameter of the upper ends of the containers. The cap-feeding unit will be of a suitable type to handle caps of the correct size to be applied to the containers. The containers will be placed indiscriminately on the conveyer and will be moved beneath the units 2 and 3. As a container is moved beneath the unit 2, it will withdraw a cap from said unit in the manner described in my co-pending application. The container with a cap loosely thereon will then be moved beneath the sealing head 26. When the container moves beneath the head 26, the magnets serve to lift the cap against the head 26. However, the upper end of the container will still engage the skirt of the cap and will move it along therewith. As soon as the cap covers the opening 119 in head 26, the control valves will be actuated to supply steam to move the piston 69 to the right. Very little steam pressure will be required to operate the pilot valve 97. This will cause the piston rod 56 to move the sealing wedge 49 which will, in turn, force the sealing head 26 downwardly. This will force the cap onto the container, as previously indicated. Thus, as the container moves into and reaches sealing position, it will automatically actuate the sealing head unit, provided a cap is disposed on the upper end of the container. Before the cap is forced on the container, the cap is subjected to sterilizing fluid and the air in the upper end of the container is displaced by steam. This is accomplished by means of the steam jets 177 from which steam continuously issues.

In sealing the cap on the container, forcing of the gasket over the upper end of the container, in itself, serves to hold the cap on the container. However, the condensation of the steam in the container beneath the cap, which occurs immediately, produces a partial vacuum which is the main force serving to hold the cap on the container and which also aids in preventing spoilage of the contents of the container. The sealing occurs substantially simultaneously with the injection of the steam into the container and, consequently, the steam will not have much chance of escaping from the container before it is sealed. During the sealing operation, movement of the

container along with the conveyer is interrupted. Suitable mechanism for this purpose may be associated with the conveyer unit. For example, it may be of the type disclosed in Serial No. 314,299. However, immediately after the sealing operation occurs, the container will again be moved along with the continuously moving conveyer and will be moved away from sealing position. The container-sealing mechanism will not function if a container which has no cap thereon, passes therebeneath.

The sealing head 26 will be moved downwardly sufficiently to force the cap downwardly into sealing position on a container. Then when spring 77 returns wedge 49 to its original position, the sealing head 26 will be moved upwardly by spring 37. Then the sealed container will be moved along by the conveyer and the opening 119 will be exposed permitting the control valves to be returned to their original positions. It will also be noted that low pressure steam can be employed for operating the sealing mechanism, since the wedge 49 will serve to multiply the force produced by movement of the piston 69. As previously explained, the extent of the downward movement of member 26 may be adjusted for a given height of container and the maximum pressure created by such member on the cap and container may be varied.

The sealing head will not be actuated if a container without a cap is moved therebeneath, because the opening 119 in sealing head 26 will not be covered. Therefore, the upper end of a container without a cap will not be damaged.

In Figures 11 and 12, I have illustrated a modification of the valve control for actuating the sealing head. In these figures, I have designated the corresponding parts with the same numerals as in Figures 9 and 10 with the exception that an additional zero is added to each numeral. In this instance, I do not employ a pilot valve equivalent to the valve 97 of Figures 9 and 10.

When the opening 1190 in the sealing head is not covered by the cap, as in Figure 11, the piston valve 820 will be to the right in the position indicated. Inlet 910 will be covered by the piston 820 while outlet 910a will be exposed. Therefore, the piston 690 will be in the position indicated in Figure 11. Steam will flow from the chamber 800, through passage 800a, through inlet 610b at the left-hand end of bore 610 and through inlet 610c at the right-hand end of bore 610. It will exhaust from the left-hand end of bore 610 through outlet 610e, passage 610d and exhaust opening 610f associated with exhaust outlet 910a. The steam in the right-hand end of bore 610 will exhaust through passage 1110b, passage 1200 and through opening 1190 to the atmosphere. Thus, the piston 820 will remain in this position. However, when the opening 1190 is covered by the cap, pressure will build up in the chamber at the right-hand end of bore 610 and will force the piston 820 to the left, as shown in Figure 12. At this time opening 1170a will also be closed. It will be understood that the pressure in the right-hand end of bore 610 is greater than that in the other end because the outlet passageway 1110b is closed while the outlet 610e at the other end of bore 610 is still open. However, when the piston 820 moves to the left, it eventually closes exhaust opening 610e and outlet 910a and also closes opening 610b and opens inlet 910. Then the steam will flow from chamber 800, through passage 800a, through passage 610a and through inlet 610c and will continue to hold piston 820

in the position indicated in Figure 12. Steam will also flow into inlet 920, through opening 910 into chamber 830, through opening 850, through passage 870 and finally through opening 880 into the bore 600 and will force the piston 690 to the right. When the piston 690 reaches the position indicated in Figure 12, opening 890 will be connected by groove 800 to passage 890a. This will permit steam to flow through passage 960a and passage 1080 into the left-hand end of bore 610 and will tend to force piston 820 to the right. The sealing head moving downwardly will expose opening 1170a and the sealed container will move away from the sealing head and opening 1190 will be exposed, permitting piston 820 to be returned to the position indicated in Figure 11. Outlet 610e is so disposed in relation to piston 820 and inlet 610b that accidental travel of piston 820 to the left will close outlet 610e and pressure from inlet 610b will return piston 820 to the right. A drain 820a is provided for any condensate that might be present in the bore 610 and this drain also serves as an exhaust opening.

It will be apparent that both forms of valve controls which I have provided for actuating the sealing head are extremely simple. They will both function to actuate the sealing head each time a container with a closure thereon is positioned in association with the sealing head.

It will be apparent from the above description that I have provided a novel structure for imparting the desired movements to the sealing head. This structure includes the reciprocable wedge structure and the control mechanism which embodies the vent that is covered each time a container with a cap thereon is moved into association with the sealing head.

Many other advantages not mentioned in connection with the preceding description will be apparent from the drawings and the following claims.

Having thus described my invention, what I claim is:

1. Apparatus of the type described for sealing containers comprising a support for a container, a sealing member adapted to be moved to force a cap on the container, a fluid-operated unit for moving said sealing member, a mechanical connection between said unit and said sealing member, said mechanical connection serving to increase the pressure developed by said unit as it is applied to said sealing member, a valve for controlling the supply of fluid to said unit, and control means for actuating said valve, said control means including a fluid passageway connected to said valve and having an outlet associated with said sealing member adapted to be closed by a cap on a container moved into association with said sealing member.

2. Apparatus of the type described for sealing containers comprising a support for a container, sealing means adapted to force a cap on the container, a fluid-operated cylinder and piston unit for actuating said sealing means, a valve for controlling the supply of fluid to said unit from a main pressure source, and control means for actuating said valve, said control means including a fluid passageway connected to said valve and having an outlet associated with said sealing means, said outlet normally permitting escape of fluid from said valve but being adapted to be covered by a cap on a container moved into association with said sealing means so as to build up pressure within said passageway to actuate said valve.

3. Apparatus according to claim 2 wherein a

pilot valve is connected to said passageway and to said main pressure source and controls the supply of fluid to said valve.

4. Apparatus according to claim 2 wherein the control means also includes means under the control of said cylinder and piston unit for returning said valve to its original position when said sealing means is moved.

5. Apparatus according to claim 2 wherein said control means also includes a pilot valve connected to said passageway and to said main pressure source and controls the supply of fluid to said valve and means under the control of said cylinder and piston unit for returning said first-named valve to its original position when said sealing means is moved.

6. Apparatus of the type described for sealing containers having caps loosely applied thereto comprising a support for a container, a sealing head associated with said support, a fluid-operated cylinder and piston unit for moving said sealing head and container relative to each other to force a cap on the container, a valve for controlling the supply of fluid to said unit from a main pressure source, control means for actuating said valve, said control means including a conduit connected to said valve and having an outlet associated with said sealing head, said outlet normally permitting escape of fluid from said valve but being adapted to be covered by a cap on a container moved into association with said sealing head so as to build up pressure within said conduit to actuate said valve, and means associated with said sealing head for lifting the cap from the container into covering relationship to said outlet.

7. Apparatus according to claim 6 wherein said

control means includes means under the control of movement of said cylinder and piston unit for returning said valve to its original position when said sealing head is moved.

8. Apparatus of the type described for sealing containers having caps loosely applied thereto comprising a support for the container, a sealing head associated with said support and adapted to be moved downwardly to force a cap on the container, a fluid-operated cylinder and piston unit for moving said sealing head downwardly, a valve for controlling the supply of fluid to said unit from a main pressure source, control means for actuating said valve, said control means including a pilot valve connected to said first-named valve and to said source of pressure, a telescoping tube connected to said pilot valve and to said sealing head and having an outlet associated with said sealing head, said outlet normally permitting escape of fluid from said valve but being adapted to be covered by a cap on a container moved into association with said sealing head so as to build up pressure within said conduit to actuate said pilot valve, and means associated with said sealing head for lifting the cap from the container into covering relationship to said outlet.

9. A structure according to claim 8 wherein the telescoping tube is provided with an aperture which is uncovered upon downward movement of the sealing head to permit return of said pilot valve to its original position.

10. A structure according to claim 2 wherein said passageway is provided with an additional outlet which is opened upon operation of said sealing means.

HARRY E. STOVER.
